UNITED STATES PATENT OFFICE

MAX WERBER, OF POUGHKEEPSIE, NEW YORK

COMBINATION GARMENT

Application filed November 13, 1928. Serial No. 319,113.

This invention relates to a combination garment, comprising a coat having a pair of leggings attached thereto, and is especially designed for use by drivers of automobiles and other vehicles, wherein cold or storms it is desired to keep the legs covered and still have free action of the legs, which is not possible where a lap robe is employed.

The object of the invention is to provide a combination garment including a coat and having a pair of leggings attached thereto and forming a part thereof, and adapted when not in use to be folded against the inner side of the coat and secured in such a position.

Another object of the invention is to provide in such a combination garment, a pair of leggings shaped to the leg and provided with attaching means to secure the same around the leg, and also means to prevent the same from forming a bunch under the knee.

Still another object being to provide means for securing the leggings to the coat, whereby as the leggings are bent by the leg in the act of sitting, no strain will be exerted on the coat to pull it out of shape.

With these and other objects in view, my invention consists in certain construction and combination of parts as will hereinafter be fully described and claimed and illustrated in the accompanying drawings which form a part hereof and in which like figures of reference refer to corresponding parts in all of the views, and it is understood that slight changes may be made without departing from the spirit of the invention.

In the drawings:

Referring to the drawings:

The combination garment comprises a coat 1, made of any suitable material such as cloth or leather, and provided with a lining 2, of fur or other suitable material, and to the lower edge of said lining 2, is secured a pair of leggings also of leather or cloth with a lining; said leggings 4, being attached to the coat or coat lining by a portion 3, which is made of suitable material such as a rubber cloth that will stretch in one direction, so that as the leggin is bent in the act of sitting, this portion will become elongated and prevent any pull or stretch on the lining of the coat, preventing the leggin from being torn off, or the coat pulled out of shape.

The leggin is also shaped to fit the leg, and provided with a cut out portion 5 under the knee, to prevent bunching as the leg is bent; and the edges are provided with a series of snap fasteners 6, to secure the same around the leg, and to coat with tabs 7, secured to the inner surface of the coat to hold the leggings in a folded position.

Having thus described my invention, what I claim as new and desire to secure by Letters Patent, is:

A combination garment comprising a coat and a pair of leggings, the upper front part of said leggings formed with a tongue of stretchable material attached in a permanent manner to the lower inner edge of said coat, allowing said tongue to elongate as the leg is bent, preventing excessive downward pull upon the coat and upward pull upon the leggin.

In testimony whereof I affix my signature.
MAX WERBER.
